MEANS FOR MOVING AND CONTROLLING
THE MOTION OF MACHINERYChristopher Francis Brereton, London, England,
assignor to Vickers-Armstrongs Limited, London, England, a British companyApplication August 13, 1947, Serial No. 768,405
In Great Britain August 19, 1946

5 Claims. (Cl. 60—97)

1

This invention relates to hydraulic power controlled means for controlling the motion of machinery where it is desired to produce controlled rotation of any suitable heavy loaded rotary support, e. g. for use in the movement of swing bridges, railway turntables, the slewing of cranes and the like purposes, and also the linear movement of hoists, furnace charging arms and the like. The object of the invention is to provide hydraulic power driven means for controlling the rotation of a turntable, swing bridges or the like mass in which by the operation of a simple valve the direction of rotation of the turntable or the like can be controlled in a very responsive manner, whilst at the same time obtaining through the medium of the hydraulic driving means a positive location of the turntable or the like in the desired position.

According to the present invention, hydraulic power apparatus for imparting movements to a mass alternately in opposite directions embodies two separate fluid pressure operated driving units each having a distinctive device operatively connecting it to the mass to be driven, one of said units having a power output less than the other so that it will yield to such other unit when under load and being adapted to be permanently connected to the source of fluid pressure so as to be maintained in permanent operative connection with its associated device connecting it to the mass to be driven, and the other unit being adapted to be alternately connected to the pressure and exhaust, and having combined with it fluid pressure operated means to maintain it in operative engagement with the appropriate device transmitting its drive to the mass and yieldingly opposing operation of the said unit which is adapted to be permanently connected to the source of fluid pressure.

In order that the invention may be clearly understood and readily carried into effect drawings are appended hereto illustrating somewhat diagrammatically two embodiments thereof and wherein,

Figures 1 and 2 are perspective views partly in section showing the apparatus in its two terminal conditions, and

Figures 3 and 4 are front elevation views partly in section showing an alternative form of the invention in which the apparatus is also shown in its two terminal conditions.

Referring to Figures 1 and 2 of the drawings which show the invention as applied to a turntable or the like, the turntable 1 is mounted upon

2 a roller bed 2, and is formed with an annulus 3 with which meshes at a suitable angle apart, e. g. 90° or other convenient spacing, a pair of gear wheels 4 and 5 each forming part of a step up train having a gear wheel 6 in one case and a gear wheel 7 in the other case in mesh with a pair of rack bars 8 and 9 respectively, the two rack bars 8 and 9 being respectively operative parts of two separate hydraulic machines A and B mounted upon an annular base plate 10 or other suitable support. The manner of mounting these two machines may be such that they can be individually angularly adjusted about the axis of the turntable, or by other suitable means they may be adjusted about such axis for varying the points of stopping and starting the drive to the turntable. For example, the machines A and B can be adjustably clamped to the base 10 by bolts 11 the heads of which slide in an undercut groove 12 in the base 10.

The machine A embodies two cylinder blocks 13 and 14 slidably along a guide bar 15 fixed to the base plate by the bolts 11, lugs 16 being provided on the guide bar to receive these bolts. The blocks 13 and 14 have opposed ends between which is interposed a stop or lug 17 projecting upwardly from the guide bar 15, the ends of this guide bar having relatively perpendicular brackets 18 and 19 to which are fixed the rams 20, 20a, and 21, 21a, appropriate to the cylinder blocks. The cylinder block 13 comprises an upper cylinder 22 and a lower cylinder 23 the upper cylinder having a larger bore than the lower cylinder, and the block 14 likewise embodies an upper cylinder 24 and a lower cylinder 25 having the same bores and strokes of the cylinders 22 and 23 respectively. The upper pair of cylinders are co-axial, and the lower or smaller pair of cylinders are also co-axial and, as distinct from the upper pair of cylinders, are supplied with constant hydraulic pressure. The upper pair of cylinders 22 and 24 are adapted to be supplied with controlled hydraulic pressure through lines 22a, 24a and to be connected to exhaust at 40, 45 through suitable valve control means 26, so that they may be connected either to pressure or exhaust at will.

The hydraulic machine B embodies only a single pair of separate cylinders 27 and 28 the rams 29 and 30 respectively of which, are as in the aforesaid machine, fixed to upstanding brackets 31 and 32 on a horizontal guide bar 33 having between its ends a vertical stop 34 against which the opposed ends of the two cylinders are adapted to abut, these two cylinders being of

smaller bore than the cylinders 22 and 24 of the machine A, but of larger bore than the smaller diameter cylinders 23 and 25 of this latter machine, the "single pair" cylinder machine B having its cylinders under constant pressure via conduits 31a and 32a in common with the smaller diameter cylinders 23 and 25 of the other machine A connected via conduits 23a and 25a to the pressure source. In this connection, although in the drawings the supply to the machines A and B is shown as apparently coming from the same source, in practice in order to avoid flexible parts in the pipe lines, the machines can be converted to distinctive sources of supply.

Normally, by reason of the two cylinders 27 and 28 of machine B being under constant hydraulic pressure their opposed ends will abut against the said intermediate stop 34 and thereby remain in a balanced position. In this position the opposed ends of the two cylinders also abut against a lug 9a depending from the rack bar 9 which extends parallel with the two cylinders and in mesh with the gear wheel 7 of the associated aforesaid train of gear wheels meshing with the annulus of the turntable 3, that is to say both of the two cylinders act as stops to prevent end-wise displacement of this rack bar until the other machine A, is brought into operation.

The machine A also has depending from its rack bar 8 a lug 8a interposed between the opposite ends of the cylinder blocks 13 and 14.

It will be apparent from the foregoing, that when the turntable is positioned in one terminal position, the machine B will have its two co-axial cylinders 27 and 28 bearing against the fixed stop 34 on the guide bar 33 and the stop 9a depending from the rack bar 9 as shown in Figure 1, so that this rack bar is located in its centre position with respect to the machine B. At this stage the larger diameter cylinders 22 and 24 of the machine A are connected to exhaust, and their associated smaller diameter cylinders 23 and 25, under the influence of constant pressure, cause one of the cylinder blocks, (e. g. the block 14 as shown) to bear idly against the fixed stop 17, whilst the other cylinder block 13 is maintained in engagement with the lug 8a depending from the rack bar 8, but is unable to move the rack bar by reason of the greater power in the cylinders 27 and 28 of the machine B.

On hydraulic pressure being admitted to the appropriate one of the larger diameter cylinders of the machine A, i. e. the cylinder 22, the control of the turntable passes to this machine, the combined power of the two cylinders 22 and 23 of the blocks 13 overcoming the power of the appropriate cylinder, i. e. the cylinder 28, of the machine B and causing the turntable to rotate into the position shown in Figure 2, in which the cylinder 27 of this machine B engages the fixed stop 34 and the other cylinder 28 is carried along by reason of the transmission of drive through the rack bar 9 and lug 9a of this machine, so that the two stops 34 and 9a and the two cylinders 27 and 28 are spaced apart, the cylinder 27 engaging the fixed stop 34 and the other cylinder receiving the driving pressure of the translatively movable stop 9a. On again connecting both of cylinders 22 and 24 of the machine A to exhaust the machine B will again take control via cylinder 28 and return the turntable to the position shown in Figure 1 in which the cycle of operations is ready to be re-commenced.

As a modification of the foregoing arrangement the stops 17 and 34, previously referred to as

fixed to the guide bars 15 and 33, can be adjustable along the guide bars, e. g. as shown in Figures 3 and 4 two guide bars 15' and 33' can be secured across a suitable base frame 10' in parallel relationship, and have threaded thereon nuts 36 acting as adjustable abutments for collars 37 on the bars and formed with grooved heads 38 slidable along guides 39, the collars 37 carrying the stops 17 and 34. The said two rack bars 8 and 9 can engage, diametrically opposite points of a common gear wheel 1' fixed to a shaft 1a to be driven by the hydraulic power control, it being understood that in both of these embodiments the hydraulic pressure fluid is applied to the working spaces of the cylinders through bores in the rams or pistons of such cylinders, which rams or pistons are fixed in relation to end brackets or plates.

The cycle of operations of the apparatus shown in Figures 3 and 4 can be the same as that applying to the apparatus shown in Figures 1 and 2, but it will be evident, by reference to Figure 4, that by adjusting the stops 17 and 34 the effective stroke of the driving cylinders can be varied and likewise the direction of the drive of the shaft 1a for a given machine A or B can be changed, e. g. instead of the machine A driving the shaft 1a or the turntable 1 in the anticlockwise direction it can also drive the machine in the reverse direction.

It will be appreciated from the foregoing that the invention can be adapted for controlling the linear movement of hoists, furnace charging arms and the like, e. g. the gear wheel 1' can drive a rack bar, or being connected by eccentric or crank and link to a reciprocating or intermittently fed uni-directionally slidable arm.

I claim:

1. In hydraulic power apparatus for imparting movements to a mass feeding mechanism, or other driven device alternately in opposite directions or intermittently in a desired direction, the provision of two separate fluid pressure operated driving units each having a distinctive device operatively connecting it to the mass to be driven, one of said units having a power output less than the other so that it will yield to such other unit when under load and being adapted to be permanently connected to the source of fluid pressure so as to be maintained in permanent operative connection with its associated device connecting it to the mass to be driven, and the other unit being adapted to be alternately connected to the pressure and exhaust, and having combined with it fluid pressure operated means to maintain it in operative engagement with the appropriate device transmitting its drive to the mass and yieldingly opposing operation of the said unit which is adapted to be permanently connected to the source of fluid pressure.

2. Hydraulic power apparatus for imparting movements to a mass feeding mechanism or other driven device, alternately in opposite directions or intermittently in a desired direction, comprising hydraulic pressure operated means adapted to be connected operatively constantly to the source of hydraulic pressure, a further hydraulic pressure operated means adapted to be connected alternately to the source of hydraulic fluid pressure and to exhaust and yieldingly opposed by the aforesaid means when connected to the source of hydraulic fluid pressure and adapted to drive the support or driver in the direction opposed to that obtaining by the operation of the first-mentioned means, the second-mentioned

hydraulic means having combined with it hydraulic fluid pressure operated means constantly under the influence of hydraulic pressure and functioning to maintain operative connection between the second-mentioned hydraulic means and the mass, and the power output of the first-mentioned means exceeding that of the third-mentioned means, whereby upon connecting the second-mentioned means to operative hydraulic fluid pressure a power bias is introduced which will overcome the load and the power of the first-mentioned means to drive the support or driver, and conversely upon connecting said second-mentioned means to exhaust, control is taken over by the first-mentioned means to return the support or driver to its previous position against the influence of the third-mentioned hydraulic fluid pressure operated means.

3. Hydraulic power apparatus for imparting movements to a mass feeding mechanism or other driven device, alternately in opposite directions or intermittently in a desired direction comprising a rotary driven element and two hydraulic engines connected to said driven element and adapted to be operated alternately so that one imparts rotation to the rotary element in one direction and the other engine in the counter-direction, the connection from each engine to the rotary element comprising a slidable driver operatively connected to the rotary element and having an abutment adapted to receive the driving load from the appropriate hydraulic engine, each hydraulic engine comprising a pair of opposed rams adapted in one stage to simultaneously engage the said abutment and a normally fixed stop also interposed between the opposed ends of the rams, the pair of rams appropriate to one machine having a greater capacity and power output than the pair of rams appropriate to the other machine and having combined with them a pair of auxiliary rams having a lesser capacity

and power output than the latter mentioned pair of rams, the maximum capacity rams being adapted to be alternately connected to the source of supply of hydraulic pressure fluid and to exhaust, whilst all of the remaining rams are adapted to be permanently connected to the said source, the arrangement being such that when the abutment of the slidable driver and associated stop on one machine are both engaged by the opposed ends of the rams on opposite sides thereof, the corresponding abutment and stop of the other machine are spaced apart with a corresponding spacing of the opposed rams of such machine and the associated stop engaged by one ram and the associated abutment engaged by the other ram of such machine, the said pair of auxiliary rams serving to maintain engagement between their associated maximum capacity rams and the associated stop and abutment and yieldingly opposing displacement of such abutment away from the stop when both of the maximum capacity rams are connected to exhaust and the pair of rams appropriate to the other machine perform the driving operation.

25 4. Hydraulic power apparatus according to claim 3 wherein said abutments are carried by slidable rack bars each free to slide relatively to the associated rams and having driving engagement with the rotary member to be driven.

30 5. Hydraulic power apparatus according to claim 3 wherein said stops are adjustable translatively.

CHRISTOPHER FRANCIS BRERETON.
